FIG. 4.

INVENTOR.
Martin Saloun
BY
Frank Schaefer,
Attorney.

UNITED STATES PATENT OFFICE.

MARTIN SALOUN, OF CHICAGO, ILLINOIS.

AERIAL BOMB.

1,312,212.

Specification of Letters Patent. Patented Aug. 5, 1919.

Application filed January 28, 1918. Serial No. 214,214.

To all whom it may concern:

Be it known that I, MARTIN SALOUN, a subject of the Emperor of Austria, residing in the city of Chicago, in the county of Cook 5 and State of Illinois, have invented new and useful Improvements in Aerial Bombs, of which the following is a specification.

This invention relates to an improvement in aeroplane or aerial bombs, wherein provision is made for so controlling the firing action, that the bomb may be exploded at any one of a plurality of predetermined distances from the launching point.

The bomb of the present invention is, in 15 addition to any usual or preferred means for exploding on contact, provided with a firing means including an explosive cap, and an ignition charge leading to the explosive charge. The explosive cap is set off practically on launching of the bomb, and the flame from said cap fires the ignition charge, and thus reaches the explosive charge. The explosive cap is arranged in a cylinder, closed 20 against the surrounding ignition charge except for one or more openings in line with the cap. Between the cylinder and ignition charge is arranged a sleeve, formed with a longitudinally disposed series or sets of 25 openings leading directly to the ignition charge. As the cap containing chamber may be manually adjusted lengthwise the sleeve, so that the openings in said chamber in line with the cap may be brought into alignment with the openings in the sleeve 30 leading to the ignition charge, the said ignition charge may be fired at any point in its length, thereby controlling the time of 35 firing the explosive charge as may be desired.

40 The invention also includes a safety cap for locking the cap firing hammer against possibility of accidental operation in the ordinary handling of the bomb.

The invention in its preferred form is 45 illustrated in the accompanying drawings, in which:—

Figure 1 is a view in elevation, partly in section, illustrating the improved bomb.

Fig. 2 is an enlarged vertical sectional 50 view, illustrating the firing means.

Fig. 3 is a section on line 3—3 of Fig. 1.

Fig. 4 is a section on line 4—4 of Fig. 2.

Fig. 5 is a section on line 5—5 of Fig. 1.

Fig. 6 is a plan, illustrating particularly 55 the safety cap in its relation to the hammer.

The invention is here shown as a spherical

bomb including a body 1 having a central chamber 2 to contain the explosive charge 3 and a series of radiating chambers 4 for shrapnel, shot or the like. The chambers 4 open through the surface of the body for charging, and are closed by caps 5, preferably threaded in place.

The adjustable firing means, with which the present invention is particularly concerned, is mounted in a radial bore 6 in the body, in communication with the explosive chamber 2. The wall of the bore 6, near the surface of the body is threaded to receive a sleeve 7, flush at its outer end with the surface of the body, and fully open at its inner end to the explosive chamber. Within the sleeve 7 is arranged a fire directing sleeve 8, which has threaded connection adjacent its outer end with the sleeve 6. The sleeves 6 and 8, below their thread connection are of such relative diameters as to provide an elongated annular space 9, closed at the upper end, and in open communication at the lower end with the explosive chamber. This space, which will be hereinafter termed the ignition space, is adapted to be filled with material 10 forming the ignition charge.

The fire directing sleeve 8 is formed 85 throughout its length with a series of longitudinally spaced openings 11, such openings being here shown as arranged in diametrically opposed pairs. An adjusting cap 12 is rotatably mounted upon that portion of the fire directing sleeve projected beyond the body 1, the said cap interfiting with the end of the sleeve, as at 13 to hold the cap against other than a rotative movement with respect to the sleeve.

The cap is formed with a central opening 14 having a threaded wall, and a firing cylinder 15 is arranged for threaded connection with the cap, through this opening. The cylinder 15 is exteriorly threaded for 100 the greater portion of its length for coöperation with the cap, and below the threaded portion is mounted for sliding fit within the fire directing sleeve 8. The firing cylinder 15 is closed at the bottom, and the wall of the cylinder immediately above said bottom is formed with openings 16. These openings are shown as comprising a diametrically opposed pair immediately above the bottom, and preferably slightly greater than the 105 openings 11 in the fire directing sleeve. The openings 11 in the fire directing sleeve.

The firing chamber is held against rota-

tion within the fire directing sleeve, preferably through diametrically opposed slots 17 in the wall of said sleeve, engaged by ribs 18 on the cylinder. Through turning of the cap 12, the firing chamber may be moved longitudinally to cause the openings 16 in the latter to register or aline with any desired set of openings 11 in the fire directing sleeve. To secure accurate registry the cap 12 is preferably provided with a pointer 19, to sweep over an adjacent flattened surface 20 on the body 1, the latter surface having indicating marks 21, to determine the registry in an obvious manner.

15 An explosive cap 22 is to be secured within the firing cylinder, on the bottom thereof, so that the flame from the cap may readily find its way through the opening 16. The cap is adapted to be discharged by a suitable hammer 23 secured upon the inner end of a rod 24 arranged within the cylinder. The upper end of the rod extends through a holding member 25, in the form of a cap exteriorly threaded on the cylinder and having 25 a sleeve 26 depending within the cylinder. The upper end of the rod is formed with a circular flat head 27, and the sleeve extension of the holding member with an elongated slot 28, of a size to readily permit the passage of the head 27 therethrough, when said head is alined with the slot, but to hold the rod against such movement when the head is turned at right angles to the slot, as will be apparent from Fig. 5.

30 The firing action of the pin or hammer, when the latter is free to act, is secured through a spring 29 coiled about the rod 24 and bearing against the firing hammer 23 and the inner end of the extension 25. With 35 the firing hammer in set position, that is, with the head beyond the holding member, and turned transverse the slot 28, the spring is under tension, and upon turning the head 27 to aline with the slot, the spring exerts 40 its tension to force the hammer inwardly and fire the cap 22.

To prevent accidental release of the hammer there is provided a safety clip, comprising a more or less rigid strip 30 removably secured to the holding member 25 and formed with an elongated slot 30 to receive the head 27 of rod 24. With the safety clip

in place as described, it is apparent that the firing pin is held against firing movement as the head 27 is held by the clip 30 crosswise of the slot 28 through which it must pass for firing, and that upon removal of the clip or upon turning the same, to permit the head 27 to aline with the slot 28 the firing pin is released for action by the pressure of spring 60 against the hammer 23.

As described it will be apparent that by turning the cap 12 the firing cylinder may be adjusted longitudinally to aline the openings 16 thereof with any desired set of openings 11 in the fire directing sleeve. The predetermined time of explosion of the bomb is thus provided for, as by means of the selected openings 11 of the fire directing sleeve, the length of the ignition charge between the flame of the cap and the explosive charge, may be of the desired length, and hence the time required to set off the explosive charge readily controlled.

In use as an aeroplane bomb directing 75 vanes or wings 31 may be secured thereto to maintain the bomb in vertical position during flight. The bomb is also preferably provided with a detonating head 32, arranged at what may be termed the bottom of the 80 body, and of any usual or desired form to fire the explosive charge on contact.

Having thus described the invention, what is claimed is:

A firing means for bombs comprising 85 spaced concentric sleeves providing an ignition charge space between them, the inner sleeve being formed with a longitudinally arranged series of openings leading to said space, an adjusting cap rotatably mounted 90 on the end of the inner sleeve, a firing cylinder held against other than sliding movement in the inner sleeve and having threaded connection with the cap, the wall of the cylinder having a set of openings to register with any of the sets of openings in the inner sleeve, and flame producing means in the cylinder arranged to ignite before the launching of the bomb.

In witness whereof I have hereunto subscribed my name this 17th day of January, 1918.

MARTIN SALOUN.
